UNITED STATES PATENT OFFICE.

FRANK M. KAUFMAN, OF PHILADELPHIA, PENNSYLVANIA.

DESIGN FOR A TEXTILE FABRIC.

Application filed July 28, 1925. Serial No. 14,246. Term of patent 8½ years.

To all whom it may concern:

Be it known that I, FRANK M. KAUFMAN, a citizen of the United States, residing at Philadelphia, in the county of Philadelphia and State of Pennsylvania, have invented a new, original, and ornamental Design for Textile Fabric, of which the following is a specification, reference being had to the accompanying drawing, forming a part thereof. The figure is a face view of a textile fabric, showing my new design. I claim: The ornamental design for a textile fabric, as shown.

FRANK M. KAUFMAN.
